FIRING TABLE

Frank P. Roesch, Chicago, Ill., and Charles R. Davison, Erie, Pa., assignors, by mesne assignments, to The Standard Stoker Company, Inc., New York, N. Y., a corporation of Delaware

Application August 2, 1932, Serial No. 627,274
Renewed January 19, 1937

8 Claims. (Cl. 110—101)

This invention relates to stoker devices and particularly to locomotive stokers of the type wherein fuel is mechanically conveyed from the locomotive tender to a point in the firebox below the grate and is then elevated through a suitable conduit to a point above the fire where it is acted upon by jets of steam or other fluid which project and distribute the fuel evenly over the fire.

10 It is the main object of our invention to provide, in stokers of the type described, a new and improved form of firing table, over which the coal or other fuel passes as it leaves the stoker and is distributed over the fire, and more specifically to provide a firing table comprising a plurality of parts so constructed and arranged as to engage each other to form a compact, simple, efficient and economical unit.

In stokers of the type described, a portion of the firing table projects a considerable distance into the firebox and being subjected to a high degree of heat it burns away much faster than other parts of the firing table that do not extend as great a distance into the firebox, and it is therefore, an object of this invention to provide a firing table in which that portion which burns away fastest can be readily detached, removed and replaced without destroying any of its other portions, and the portions of the firing table are when assembled in place, rigid and unified with the fuel delivery conduit, the construction being such that the plurality of parts composing the firing table are rigidly secured one with the other without the necessity of using added means.

Various other objects and advantages of our invention will appear from the following description taken in connection with the accompanying drawing which shows one embodiment 40 of the invention, and wherein:

Fig. 1 is a central longitudinal vertical section of a portion of a locomotive with a stoker applied thereto and shown in elevation with parts broken away and a firing table assembled there-45 with;

Fig. 2 is a view in perspective of the novel form of firing table;

Fig. 3 is a plan view of the firing table with parts broken away showing its application to 50 the stoker conduit;

Fig. 4 is a view in section on the line 4—4 of Fig. 2;

Fig. 5 is a sectional view on the line 5—5 of 55 Fig. 2; and

Fig. 6 is a sectional view on the line 6—6 of Fig. 3.

On the drawing, the locomotive is designated generally by the numeral 10 and is provided with a firebox 11 having a backwall or rear water leg 5 12. The backwall 12 has a firing opening 13 therethrough above the cab deck 14. Fuel is carried from the locomotive tender (not shown) to the locomotive 10 by means of a conduit 15 which houses a portion of the screw conveyor 10 system 16. A conduit 17 is universally connected to the forward end of the conduit 15 and terminates in an upwardly curving elbow 18 which merges into the straight tubular conduit or riser conduit 19. The straight tubular 15 conduit 19 terminates in a D-shaped mouth 20 or fuel delivery opening above the level of the fire in the firebox 11.

Partially surrounding the straight tubular conduit 19 is a protecting grate 21 shielding the 20 conduit 19 from the direct heat of the fire in the firebox 11. Surmounting and lightly fitting the conduit 19 and resting at its inner edge on lugs 22 projecting from the outer face of the conduit 19, is a metal plate or firing table 23. 25 The top 24 of the table 23 is smooth and preferably flat, as illustrated, and is in substantially the same plane with the upper marginal edge of the mouth portion 20 permitting fuel to pass freely thereover.

The outer marginal edge of the top 24 of the table 23 is substantially U-shaped and the inner marginal edge conforms substantially to the shape of the outer edge. The open end of the U is restricted as at 25 by the inwardly extending portions 26. A flange 27 depends from the underside of the table 23 between its outer and inner marginal edges. The table 23 is composed of the three sections 28, 29 and 30, the section 28 forming the forepart of the table 23 and the sections 29 and 30 forming the rear part of the table 23. The sections 29 and 30 are preferably formed symmetrically, though, it will be obvious that they need not necessarily be so.

The surfaces of the section 28 contacting the sections 29 and 30 are provided with the grooves 31 and the tongues 32 and the surfaces of the sections 29 and 30 contacting the section 28 are provided with the tongues 33 closely fitting the grooves 31 and the grooves 34 closely fitting the 50 tongues 32. The interlocking tongues and grooves prevent relative longitudinal movement between the sections 28, 29 and 30 and prevents upward displacement of the section 28 with respect to the sections 29 and 30. The contacting 55

surfaces of the sections 28 and 29, and 28 and 30 provided with the tongues and grooves are angularly arranged with respect to each other thereby preventing sidewise displacement of the section 28 when the sections 29 and 30 are secured in place.

The sections 28, 29 and 30 when assembled are seated on the conduit 19 by engagement of the lugs 22 with that portion of the underside of the table 23 between the depending flange 27 and the inner marginal edge of the table top 24. The flange 27 fits over the lugs 22. The sections 29 and 30 are provided with the openings 35 arranged to receive bolts 36 for securely attaching the sections to the conduit 19. The bolting of the sections 29 and 30, together with the angularity of the contacting surfaces of the sections 28, 29 and 30 and the interlocking arrangement of grooves and tongues cooperate to rigidly secure the sectional table 23 in place when once assembled. The table 23 is supported some distance above the top of the grate 21, as shown at 37 to compensate for relative movement between the parts due to the extreme variations in temperature causing contraction and expansion thereof.

The sections 29 and 30 of the firing table may be cored as at 38 in order to reduce the weight of the table and to reduce the cost of construction. The section 28, however, is preferably solid metal since it extends farther into the firebox and is consequently burned off more rapidly.

35 A recess 39 is formed in the wall of the conduit 19 adjacent its mouth 20 and is arranged to receive a pressure fluid jet distributor 40. The distributor comprises a distributor head 41 having substantially radial nozzles or openings 42 which are supplied with steam or other fluid by the pipes 43.

40 The firing table, in stokers of the type described, since it is wholly within the firebox is necessarily subjected to an intense heat and in time deteriorates to such an extent as to require replacement. In the present arrangement there
45 is provided a three piece firing table, which when assembled is rigidly secured in place without the necessity of using added fastening means, and one part may be replaced as deterioration occurs without the expense of replacing the entire firing table.

We claim:

1. A U-shaped firing table for a stoker formed in a plurality of sections, the curved portion of said U-shaped table forming one section and the straight portions of said U-shaped table forming the other sections, the adjacent ends of said curved section and said straight sections each being provided with interengaging tongues and grooves for preventing relative longitudinal movement between said curved section and said straight sections, the tongues and grooves at the adjacent ends of said curved section and one of said straight sections being angularly disposed with respect to the tongues and grooves at the adjacent ends of said curved section and the other of said straight sections for preventing relative lateral movement between said curved section and said straight sections.

70 2. As an article of manufacture, a section of a sectional firing table for stokers, said section having an imperforate flat top face and being substantially U-shaped in section parallel to said top face, end walls angularly related to each other, and an element of an interlocking means formed in each of said end walls.

3. As an article of manufacture, a section of a sectional firing table for stokers, said section having an imperforate flat top face and being substantially U-shaped in section parallel to said top face, end walls angularly related to each other, and a tongue and groove constituting an element of an interlocking means formed in each of said end walls.

4. As an article of manufacture, a section of a sectional firing table for a stoker, said section having a flat top face and being substantially spandrel shaped in section parallel to said top face, and a sloping end wall having a tongue and groove formed therein extending in planes parallel to the plane of said top face. 15

5. In combination with a firebox having an up-
standing wall, a conduit for delivering fuel to
said firebox comprising an upwardly extending
portion terminating in a fuel delivery opening
disposed inside the firebox adjacent said up-
standing wall, a firing table comprising a plu-
rality of end-to-end related sections surmount-
ing said upwardly extending portion and partial-
ly surrounding said fuel delivery opening, said
sectional firing table including a curved section
remote from said firebox wall and a pair of end sec-
tions adjacent to said firebox wall, the adjacent
ends of said sections being formed with inter-
fitted grooves and abutments, the junctions of
said sections being angularly related to each other, means for rigidly securing said end sections to said upwardly extending conduit portion, said interfitted grooves and abutments being ar-
ranged to prevent lateral, longitudinal and upward displacement of said curved section when said end sections are rigidly secured in position. 15 20 25 30 35

6. In combination with a firebox having an upstanding wall, a conduit for delivering fuel to said firebox comprising an upwardly extending portion terminating in a fuel delivery opening 40 disposed inside the firebox adjacent said upstanding wall, a firing table comprising a plurality of end-to-end related sections surmounting said upwardly extending portion and partially surrounding said fuel delivery opening, 45 means for projecting fuel radially across said firing table, said sectional firing table including a curved section remote from said firebox wall and a pair of end sections adjacent to said firebox wall, the adjacent ends of said sections being 50 formed with interfitting grooves and abutments, the junctions of said sections being angularly related to each other and substantially in the plane of the path of the fuel projected across the table at said junctions, means for rigidly securing said end sections to said upwardly extending conduit portion, said interfitting grooves and abutments being arranged to prevent lateral, longitudinal and upward displacement of said curved section when said end sections are rigidly secured in 55 position. 60

movement between said curved section and said end sections.

8. In combination with a firebox, a conduit for delivering fuel to said firebox comprising an upwardly extending portion terminating in a fuel delivery opening, ledge-like means extending outwardly from said upwardly extending portion beneath the fuel delivery opening thereof, a firing table having a flat top face, said table being seated on said ledge-like means and fitting closely against the delivery end of said upwardly extending conduit portion, said firing table comprising a substantially U-shaped forward portion

and a rearward portion in contacting end to end relation, the adjacent ends of said portions being provided with interengaging tongues and grooves for preventing relative longitudinal movement between said portions and for preventing upward displacement of said U-shaped portion with respect to said rearward portion, and means for rigidly securing said rearward portion to said upwardly extending conduit portion for securing said U-shaped portion against movement with respect to said conduit portion. 5
